UNITED STATES PATENT OFFICE.

HARVEY S. ALCORN, OF BRIDGEPORT, OKLAHOMA.

RAIL-JOINT.

1,320,305.

Specification of Letters Patent. Patented Oct. 28, 1919.

Application filed December 29, 1917. Serial No. 209,478.

To all whom it may concern:

Be it known that I, HARVEY S. ALCORN, a citizen of the United States, residing at Bridgeport, in the county of Caddo and 5 State of Oklahoma, have invented new and useful Improvements in Rail-Joints, of which the following is a specification.

This invention comprehends generally improvements in that class of inventions 10 known as railway rails and joints and more particularly has reference to a rail joint.

As the primary aim and object this invention contemplates the provision of a device of the above mentioned character 15 wherein the adjoining ends of rail sections are designed for engagement with each other in such a manner as to sustain the weight of rolling stock as it passes over the joint between the sections.

More particularly, this invention includes 20 the provision of a device of the above mentioned character wherein the meeting ends are designed so that when in engagement with each other they will be prevented from 25 being depressed when rolling stock passes thereover and incidentally are designed so as to be prevented from lateral movement with respect to each other.

With these and other objects in view, the 30 invention consists in the features of construction, combination and arrangement of parts, as will be hereinafter fully described, illustrated in the accompanying drawings and pointed out in the claim hereunto appended.

Changes, variations and modifications 35 may be made in the invention such as come properly within the scope of the appended claim without departing from the spirit of 40 the invention or sacrificing any of its advantages.

The invention is clearly illustrated in the accompanying drawings, in which:

Figure 1 is a side elevation of the device; 45 Fig. 2 is a side elevation with one of the angle bars removed;

Fig. 3 is a transverse section of the invention taken on line 3-3 of Fig. 1;

Fig. 4 is a perspective detail of one end 50 of one of the rail sections;

Fig. 5 is a perspective detail of the adjacent end of the other rail section.

Similar characters of reference are employed in all of the above described views 55 to indicate corresponding parts.

Referring now, more particularly, to the

accompanying drawings, there is provided a pair of rail sections 1 and 2 each of which consists of a base 3, a web 4 and a head 5. The adjacent ends of the sections 1 and 2 meet in an improved joint indicated in its entirety by the numeral 6 while angle bars 7 are arranged on opposite sides of the rails and conform to the shape thereof being arranged to engage the web and the upper 60 surface of the base flanges and the under surface of the head being held against displacement through the instrumentality of suitable bolts 8 which pass through the angle bars and the web of the rail sections 65 while the parts are removably clamped in a stationary position through the instrumentality of adjustable element such as nuts 9.

In reducing the improved joint 6 to practice the rail section 1 has its opposite sides sloped or beveled inwardly in convergent relation with each other as indicated by the numeral 11, terminating in a point, forming in effect a tapered tongue 11 of the base 70 flanges. The web portion 4 of the same section is formed with an inwardly extending V-shaped recess 12 while the head of the rail section 1 is extended as indicated by the numeral 13 for a purpose that will presently 75 appear. The other rail section 2 has its base provided with a V-shaped recess 14 which extends inwardly from the end of the section and terminates directly beneath the web portion. This section 2 also has its 80 web portion extended to provide a tongue 15 the upper and lower edges converging to a point 16 being practically designed for engagement with the V-shaped recess 12 in the adjacent end of the other section. The 85 head 5 of the section 2 is cut away to form a recess 17 which is designed to accommodate the extended portion 13 of the head of the other section. It is to be observed particularly that the tapered tongue 11 and the recess 14, the recess 12 and the tapered tongue 15, and the extended head portion 13 and the recess 17 are respectively complementary so that when the rail sections 1 and 2 are moved toward each other they will 90 lie in interengagement with each other and are capable of being held in such position by the angle bars 7 which are removably held in the position described by the bolts 8, and the nuts 9.

In use, when rolling stock passes over the joint, the latter will be prevented from

being depressed, since the extended head portion 13 is supported within the recess 17. In addition, lateral movement is prevented owing to the engagement of the tapered tongue 11 lying within the V-shaped recess 14 in the base of the other rail section 2. The extended head portion 13 of course prevents accidental movement of the extended tongue 15 in the recess 12.

10 It is believed in view of the foregoing description that a further detailed description of the operation of the invention is entirely unnecessary. Likewise, it is thought that the advantages of the invention will 15 be readily apparent.

As many changes could be made in the above construction and many apparently widely different embodiments of this invention could be made without departing from 20 the scope thereof it is intended that all matter contained in the above description or shown in the accompanying drawings shall be interpreted as illustrative and not in a limited sense. It is also to be understood that the language used in the following claim is intended to cover all the 25 generic and specific features of the invention herein described and all statements of the scope of the invention which as a mat-

ter of language might be said to fall there- 30 within.

What is claimed as new and desired to be secured by Letters Patent, is:—

35 A rail joint comprising the meeting ends of a pair of rail sections, one of said sections having its head projecting beyond the web in which web there is formed an inwardly extending V-shaped recess, and having 40 its base flange tapered off to provide a tapered tongue, the other of the rail sections 45 having its head terminating short of the web which latter is formed on the end in the shape of a tapered tongue for engagement in the V-shaped recess of the first section, the base flange of the said latter sec- 50 tion being formed with a V-shaped recess for the reception of the tapered tongue of the first said section, the tapered tongues and recesses of the flanges and webs forming interlocking joints preventing relative lateral movement between the two sections, the projecting head of one section abutting the shortened head of the other section to break the joints between the heads and the base flanges.

55 In testimony whereof I affix my signature.

HARVEY S. ALCORN.
